[57] CLAIM

The ornamental design for an inflatable float, substantially as shown and described.

DESCRIPTION

FIG. 1 is a plan view of an inflatable float showing our new design in an inflated condition with the side opposite being identical but for the absence of the three valves;

FIG. 2 is a side view thereof as seen from the left side of FIG. 5;

FIG. 3 is a sectional view thereof as seen from A—A of FIG. 1;

FIG. 4 is a sectional view as seen from B—B in FIG. 1;

FIG. 5 is a view as seen from the right side of FIG. 1;

FIG. 6 is a view as seen from the left side of FIG. 1;

FIG. 7 is a plan view of the inflatable float shown in a deflated condition;

FIG. 8 is a right side view of FIG. 7;

FIG. 9 is a view as seen from the top of FIG. 7; and

FIG. 10 is a view as seen from the bottom of FIG. 7.
